UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

DESIGN FOR IMPACT SECTIONS FOR A VEHICLE BUMPER.

Application filed December 21, 1927. Serial No. 24,581. Term of patent 14 years.

To all whom it may concern:

Be it known that I, HERBERT S. JANDUS, a citizen of the United States, residing at Detroit, in the county of Wayne and State of Michigan, have invented a new, original, and ornamental Design for Impact Sections for a Vehicle Bumper, of which the following is a specification, reference being had to the accompanying drawing, forming part thereof, wherein—

Fig. 1 represents a plan view and Fig. 2

represents a front elevation of a bumper exhibiting my design. My invention relates to the impact sections of a vehicle bumper and the support means and clamp plates are shown in dotted lines.

I claim:

The ornamental design for impact sections for a vehicle bumper, substantially as shown and described.

HERBERT S. JANDUS.
